PRINTING MECHANISM

Gustav Tauschek, Weidling, near Vienna, Austria, assignor to International Business Machines Corporation, New York, N. Y., a corporation of New York

Application September 6, 1933, Serial No. 688,294

19 Claims. (Cl. 197—58)

This invention relates to printing mechanisms and more particularly to the type incorporated in accounting machines.

Machines of the latter type are sometimes provided with printing mechanisms for printing letters of the alphabet so that by the printing of complete words or abbreviations numerical data is readily identified.

Heretofore, to accomplish printing of the letters of the alphabet a type bar was provided with a type for each letter of the alphabet although in some instances a single type was employed to represent two letters in view of the general similarity of such letters, for example "U" and "V". While such an expedient reduced the number of type carried by a single type bar to less than the number of letters comprising the complete alphabet the number of type carried by the single type bar was still inordinately greater than desired especially when high speed printing operations were required. As the type are usually carried by reciprocating type bars unusually heavy masses were required to be reciprocated and further, due to the number of type being greater than the number of selecting elements, complicated type selecting mechanisms were required which also added to the objections.

In the present case only twelve type are employed and some are alike but differ in location. The remaining are each of a configuration different than any other so that by printing from such type in different combinations letters of the alphabet may be printed.

One of the objects of the present invention is to devise a printing mechanism whereby a number of different characters can be printed which characters are in excess of the number of type required to print such characters.

A further object of the present invention is to reduce the number of printing type carried by a single member for printing the letters of the alphabet.

A still further object resides in the provision of selecting such type under control of tabulating card perforations arranged in different combinations.

A still further object is to provide a type hammer striking mechanism which is operable so as to effect printing from different type while the type are in motion, and preferably in different combinations to represent, for example, letters of the alphabet.

A further object with respect to the type hammer striking mechanism is to provide selective means for causing its operation at predetermined

times during the successive presentation of the different type to the printing line. More specifically this object is attained by causing the operation of the type hammer striking mechanism as card perforations are successively analyzed. 5

While the invention has been shown in connection with an alphabet printing mechanism it is to be understood that the same is merely illustrative and by following the teaching of the invention other characters can be printed with the same advantages and beneficial results. The invention in whole, or in part, can, with minor changes, be incorporated in machines of different types.

In said drawings:

Fig. 1 represents the card feeding mechanism of a tabulating mechanism and the card analyzing mechanism.

Fig. 2 is a view in side elevation of a well known type of printing mechanism provided with the present improvements.

Fig. 3 is a representation of part of a tabulating card shown punched to cause printing of all the letters of the alphabet by selection of the different type.

Fig. 4 is a diagrammatic representation of the end of each of the different type showing the distinct configuration of each.

Fig. 5 is a diagram showing the different components for each alphabetical character, each vertical column under a letter indicating which type of the type bar are selected for printing of such a letter.

Fig. 6 is a view showing the type mounting and return spring.

The machine in which the present improvements have been incorporated is well known and is exemplified in the patents to Lake No. 1,379,268, dated May 24, 1921, No. 1,600,413, dated September 21, 1926, and the patent to Daly et al., No. 1,896,540, dated February 7, 1933.

In machines illustrated in detail in the above described patents and generally herein, tabulating cards 10 are adapted to be fed singly by a picker 11 from a supply stack to a pair of upper feeding rollers 12 which convey the card so as to have the perforations of the card analyzed by the usual perforation analyzing brushes 13 while the card is in motion. The card analyzed then passes to a lower set of feeding rollers 14 which then convey the card to a storage hopper, usual in the type of machine referred to.

Card feeding operations are instituted by the usual manual start key designated as ST in the last mentioned patent so as to cause by an elec- 55

trical circuit the energization of a card feed clutch magnet 15.

The power for driving the card feeding rollers and other parts of the machine is derived from a 5 motor (not shown) which by a belt 16 and pulley 17 constantly rotates a ratchet wheel 18 secured thereto. The pulley 17 and ratchet wheel 18 are loosely mounted upon a shaft 18.

In Fig. 1 there is shown the card feed clutch 10 for causing card feed and is similar to the card feed clutch disclosed in Fig. 1a of the Lake Patent No. 1,822,594, dated September 8, 1931 to which reference should be had for details of construction and operation.

15 Upon completion of the electrical circuit to clutch magnet 15 the latter attracts its armature to raise a clutch lever 21 to thereby unlatch the latter from a clutch pawl 22. The latter is then drawn by a related spring 23 to engage the constantly rotating ratchet wheel 18. The clutch pawl 22 is carried by a bar 25, which is secured to a disk 26 secured to shaft 18 and to the latter there is secured a pinion 27.

The construction and operation of the card 25 feed clutch, as is well known, is such that upon energization of magnet 15, disk 26 will be rotated and successive rotations of the shaft 18 and therefore pinion 27 will ensue as long as tabulating operations are desired.

30 The pinion 27 is in mesh with a gear 28 and the latter drives the upper set of feeding rollers 12 and the lower set of feeding rollers 14. The upper set of feeding rollers is intergeared by pinions 29 one of which is rotatable with a gear 30 in mesh with the driving gear 28. The latter also meshes with a pinion 31 which is rotatable with one of a pair of inter-geared pinions 32 carried by the rollers 14 which drive the lower set of feeding rollers 14 in opposite directions. 35 The driving gear 28 is of sufficient width to drive a gear 34 so that by a train of gears 35, 36 a shaft 37 is driven. It is understood that as is usual in tabulating machines the card feed clutch is so designed and the gears are so proportioned that shaft 37 will be given a complete revolution 40 in the arrow direction shown in Fig. 1.

It is customary in the type of machine described to adjust printing type of a printing mechanism in synchronous relationship with the 50 analyzing of the index points of the card and to carry out the printing function in a novel manner a construction which is well known is adopted. This mechanism is fully described in the patent to Daly et al., No. 1,896,540, dated February 7, 55 1933 and for this reason is described generally herein except for the improvements incorporated therewith.

60 Operation of the type bars during card analyzing operations is effected by a box cam 38 secured to shaft 37. The printing type bar 39 is reciprocated by a rock shaft 40 and the shaft 40 has an arm 41 fixed to it. An arm 42 freely rotatable on the shaft 40 carries a roller which projects into the cam slot of box cam 38. The arm 41 fixed to shaft 40 has a lug 43 normally engaged by a set screw 44 in arm 42. When the box cam 38 rotates in the clockwise direction, owing to the cooperation of the lug 43 and set screw 44, it will result in rocking shaft 40. Se- 65 cured to shaft 40 are arms 45, (only one being shown in Fig. 2) each being pivoted at its free end to a slidable frame 46 by a link 47. The type bars 39 are mounted for simultaneous move- 70 ment with the frame since an extension 48 of the type bar constantly projects against a por-

tion of the frame by means of a spring-pressed lever 49, one of which is provided for each type bar and pivoted by a suitable frame so that they elevate the frame 46 and type bars carried thereby simultaneously.

The type bars in the present machine move 5 upwardly with the frame 46 so as to present for each machine operation each type 51 of a type bar 39 to the printing position, this action being performed by the related spring-pressed lever 49. 10

Each type bar is provided with ratchet teeth 50, there being one tooth for each index point position of a card column and for each of the printing type 51 of a related type bar 39. Each printing type of a type bar is called for a printing 15 operation under control of a printing control magnet 52 when a corresponding perforation is sensed. The armature of the latter when attracted shifts a call wire 53 to the right to displace a type hammer latch member 54. The purpose of presenting each type 51 of a type bar to the printing position will be made apparent by the following explanation.

Instead of having a type of the same configuration as each letter of the alphabet to print 25 the letters of the alphabet, the machine is equipped with only twelve type instead of one for each alphabetical character. The twelve type, as illustrated in Fig. 4, are adapted to each carry 30 type of distinct configurations or are in different positions where alike and these type in combination, make up some of the alphabetical characters. For example, to print the first letter or "A", printing is successively effected from the sixth and twelfth type and by the superposition 35 of the marks effected on the type the character "A" will be printed. The letter "B" is made up by successively printing from the first, third, and fifth type, and so on, the type in combination making up most of the remaining characters, it 40 being noted that due to the forms of the type adopted, a single type will print the letters "I" and "V", although by adoption of type of other different configurations these letters can also be printed by combinations of printed marks. 45 Most of the letters are in accordance with the convention form, although some are slightly different, the slight difference not affecting the quick recognition of what characters are intended.

To cause successive printing, each column of 50 a card is provided with one or more perforations in a column, and in Fig. 3 there is represented the number of perforations necessary in a card to cause printing of the letters of the alphabet in 55 accordance with the components comprising the type 51. These perforations in a single column may be in any of the twelve index point positions.

The electrical means whereby the perforations in a card column are analyzed is shown in Fig. 1 wherein it will be seen that in a circuit connected to a source of electrical power P the printer control magnet 52 is in series with the brush 13 which coacts with a contact roll 55 65 through a card perforation thereby extending the circuit to card lever contacts 56 closed when a card actuates a card lever 57. Thus each time the brush 13 senses a card perforation an electrical impulse is transmitted to magnet 52 and thus 70 the latter is successively energized as card perforations in a controlling card column are sensed.

From Fig. 2 it will be seen that the printing hammer 58 is pivoted on a stud 59 and is urged by a spring 60 so that the hammer portion 61 75

strikes the left end of the type 51 in printing position but such action is normally restrained by the engagement of the latch member 54 with an extension of the hammer 58.

5 Upon energization of the magnet 52 the hammer 58 is released and the hammer portion by the action of spring 60 strikes the type in printing position and shifts it to the right to effect an imprint. The type construction is fully shown 10 in Fig. 6 wherein it will be seen that the type when struck is impelled against the action of a spring 62 which immediately retracts the type away from the paper surrounding the platen 68. The platen is the usual construction and carries 15 the paper which is printed upon by the usual inking ribbon.

The type selected for printing is dependent upon which perforation is analyzed and upon release of the printing hammer it is necessary to 20 relatch the same for successive printing operations. It should be observed that if a printing operation is followed by a subsequent elevation of the type bar 39 that the type 51 from which a printing operation is effected is restored clear of 25 the paper by the spring 62 assisted by the usual rebound of the type 51. The type hammer portion 61 follows the selected type a slight and lesser distance as determined by the coaction of 30 the edge 63 with the corner 64 of a stationary cross bar 65 so as to permit the free restoration of the type which is shifted for printing.

A triangular shaped pin 66 is carried by the type hammer 58 and when a perforation is analyzed and the related type is at the printing position 25 the pin 66 is in registration with one of the notches 50 permitting the entry of the pin 66 therein. After such entry, which is preferably only of sufficient extent so that pin 66 partially reaches into notch 50, the selected type is 40 stored by spring 62 (Fig. 6) to clear the paper. Even though the pin 66 engages a wall of the notch 50 the spring between lever 49 and frame 46 is sufficiently strong to overcome the tension of the relatively light spring 60. This will prevent 45 any stoppage of the bar 39 during or after the printing operation permitting the type to be struck while they are being elevated. The coaction of the lower inclined edge of the notch 50 in which the pin 66 has entered will cam the hammer 58 in 50 a counterclockwise direction sufficiently to permit its relatching by the latch member 58 and shift the hammer portion 61 clear of a type 51 in normal position. In such relatched condition the printing hammer 58 is ready to strike another type 51.

When all the type have been successively brought to the printing position and the desired alphabetical character printed in the manner described, the frame 46 and type bars 39 are 55 restored by means of suitable springs (not shown) but identified by numeral 290 in Patent No. 1,822,594.

Of course, after printing a line of characters the paper surrounding platen 68 is line spaced 60 so as to separate the line of printing from the line next to be printed under control of a following tabulating card 10.

What is claimed is as follows:

1. In a machine of the class described, the 70 combination with a bar carrying a series of type, of means for reciprocating the bar to present each type to a printing line for each operation of the machine, and means for effecting a printing impression from a selected type while the bar is in motion.

2. In a machine of the class described, the combination with a bar carrying a series of type, of a type impression member, means for reciprocating said bar to present each type to a printing position for each operation of the machine, and means for causing the operation of the impression member while said bar is being moved by said reciprocating means. 5

3. In a machine of the class described, the combination with a bar longitudinally reciprocable and carrying a series of type, of a type impression member, means for reciprocating said bar to operatively correlate during one movement thereof all of said type to said member, a printer control magnet for controlling the operation of 10 said impression member, and a card analyzing means for changing the energization status of said magnet in accordance with the card perforations analyzed to cause said impression member to 15 strike a selected type. 20

4. In a machine of the class described, the combination with a bar carrying a series of type, of means for presenting said type to a common printing position during a machine operation, a hammer operable to strike a selected type, and 25 means on said bar for restoring said hammer after its operation.

5. In a machine of the class described, in combination, a series of type, means for presenting said type to a printing position, a hammer 30 movable for striking the selected type, a member having a camming notch, a projection, means for causing said projection to engage said camming notch when said hammer is moved, and means for thereafter effecting a relative movement between said projection and camming notch to 35 restore said hammer.

6. In a printing mechanism, in combination, a hammer operable for striking a selected type of a group, a movable bar carrying said group of type, 40 and a projection carried by said hammer and engageable with a cam notch in said bar, whereby movement of the latter restores said hammer after its operation.

7. In a machine of the class described, in combination, a bar carrying a series of type, a hammer for striking a selected type while said bar is 45 in motion, and a spring for restoring after a printing operation the type selected for printing clear of the medium printed upon. 50

8. In a machine of the class described, in combination, a bar carrying a series of type, a hammer for shifting a selected type by striking said type during the movement of said bar, a spring for restoring the type selected for printing clear 55 of the medium printed upon after a printing operation, and a stationary member for de-limiting the movement of said hammer to an extent less than the shifting movement of the type selected for printing. 60

9. In a machine of the class described, in combination, a series of type from which imprints in different combinations represent characters, means for presenting each of all of said type in succession to a common printing line, and means 65 for selecting certain of said type in a predetermined combination to print a desired character.

10. In a machine of the class described, in combination, a series of type from which imprints in different combinations represent different characters, means for moving said type to cause their presentation to a common printing line, and means effective while the type are in motion for 70 selecting said type in a predetermined combination for printing a desired character. 75

11. In a machine of the class described, in combination, means for successively moving a number of type differing in relative locations or in configuration to a printing position prior to printing operations from said type, and means for successively printing at the same position from selected ones of said type while each type is in motion. 5
12. In a machine of the class described, in combination, means for successively moving a number of different type to a common printing position prior to printing operations from said type, means for successively printing at the same position from selected ones of said type, and controlling means 10 for said printing means comprising means for analyzing combinations of card perforations. 15
13. In a machine of the class described, a series of different type, card analyzing means for designations representing characters, means operable in synchronous relationship with the analyzing 20 of a card for successively moving said type to a common printing position prior to printing operations from said type, and means controlled by the analyzing means for selecting said type by printing operations at the same printing position. 25
14. In a machine of the class described, in combination, analyzing means for analyzing a combination of perforations on a card representing a character, and means under control of said analyzing means for causing printing from different types while the latter are in motion past a common printing position. 30
15. In a machine of the class described, in combination, a bar carrying a series of different type, a hammer operable to strike said type, means for presenting each of said type to a printing position for each machine operation by reciprocating said bar an invariable amount, and means for causing said hammer to strike the selected type to effect a printing operation. 35 40
16. In a machine of the class described, a series of type, means for presenting each type to a printing position for each machine operation, card analyzing means for analyzing an index point position when a related type is at the printing position, a hammer under control of said analyzing means and operable when a perforation is analyzed, and means for thereafter restoring the hammer in position to effect, if necessary, another imprint during the same machine operation. 10
17. In a machine of the class described, in combination, a series of different type, means for presenting each type to a common printing position, means for selecting said type in a predetermined combination, a hammer operable independent of said type to effect shifting of the type to print at a common printing position, means for latching said hammer, means for unlatching said hammer at predetermined times, and means for causing the latching means to 20 relatch said hammer after each printing operation. 25
18. In a machine of the class described, means for presenting a series of type in succession to a common printing position, a hammer for shifting the selected type for a printing operation, a latch for said hammer, card analyzing means for displacing said latch to release said hammer for a printing operation, and means for causing the latch to relatch said hammer after a printing operation. 30
19. In a machine of the class described, the combination with a bar carrying a series of type, of means for effecting a printing impression from a selected type, and means for reciprocating the bar to present during one movement thereof the selected type to a printing line and thereafter continuing the further movement of said bar to present for printing therefrom other type on said bar. 35

GUSTAV TAUSCHEK. 40
